UNITED STATES PATENT OFFICE.

HERBERT O. RUSSELL, OF DETROIT, MICHIGAN, AND CHARLES LEIGH PAULUS, OF DAYTON, OHIO.

SELECTIVE ELECTRIC CONTROL FOR BOMB RACKS.

Application filed April 18, 1922. Serial No. 555,420.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Selective Electric Controls for Bomb Racks, of which the following is a specification.

This invention relates to electrical control mechanism for bomb racks, the object in view being to provide an apparatus of the character referred to for selectively releasing bombs from the bomb rack of an airplane or other aircraft, the mechanism providing for releasing a train of bombs one at a time or at regular intervals, or a salvo of bombs. In the latter case while it is not practicable to drop all at the same instant, the bombs follow each other in rapid succession.

With the above and other objects in view, the invention consists in the novel construction, combination and arrangement herein fully described, illustrated and claimed.

In the accompanying drawings:

Figure 1 is a view in elevation of the bomb rack.

Figure 2 is a cross section through the same taken in line with the core of the controlling solenoid.

Figure 3 is a fore and aft section through one of the streamline members of the craft showing the safety device.

Figure 4 is a face view of the switch board.

Figure 5 is a section at the switch board taken on the line A—A of the Figure 4.

Figure 6 is an end view of the same.

Figure 7 is a diagram showing the form of slot or guideway in the train switch.

Figure 8 is a similar view of the slot or guideway in the salvo switch.

Figure 9 is a diagram of the wiring system.

Figure 10 is an elevation of a bomb rack adapted to carry both large and small bombs.

Figure 11 is a plan view of the same.

Referring primarily to Figures 1, 2 and 3 of the drawings, the bombs one of which is shown at 1 are suspended from the streamline hanger member 2 containing a hanger rail 2' by means of independently releasable hooks 3, the latter being pivoted to the

hanger at 4. The point of each hook fits in 55 a notch in a bracing member 5 when the hook is closed so as to relieve the hook of part of the strain. A locking lever or trigger 6 is used in conjunction with each hook 3 and is provided with a tooth or lip 7 adapted to engage a co-acting tooth or lip 8 on the hook when closed in order to secure the latter in bomb-holding position.

A rotatable shaft 9 extends along the hanger member 2 and is journaled in bearings 10 therein. The shaft carries a series of cams 11 mounted thereon so as to rotate with and be actuated by the shaft, there being a cam disposed above each hook. The peripheral edge of each cam works in a 65 notch 12 in the corresponding trigger 6. The offset portion 13 of the cam is adapted to trip the trigger when moving through the notch therein so as to throw the trigger to hook-releasing position. The offset portions 70 13 of the series of cams on the shaft 9 are set a certain number of degrees apart in order that the bombs will be released in succession instead of simultaneously which would bring too much load to bear upon the 75 shaft at one time.

In order that any desired bomb may be attached to its respective hook of the rack independently of the other bombs, the cam 11 for each bomb hook is mounted for 80 limited longitudinal play on the shaft 9 but is incapable of rotation with respect to the shaft. A compression spring 14 normally maintains each cam in engagement with a 85 stop 15 on the shaft shown in the form of a 90 collar fastened to the shaft which will sustain the end thrust of the cam when the offset portion thereof is operating the corresponding trigger. However, by manually turning the trigger to an inoperative position, the cam will be shifted away from the stop 15 due to the yielding of the spring on the opposite side of the cam. The hook may be opened for attaching the bomb and then restored to its closed position. The spring 14 will return the cam to its normal operative position against the stop.

A pawl and ratchet mechanism 16 and 16' is disposed at some convenient location on the shaft 9 and is adapted to convert reciprocatory movement of the core 17 of a solenoid 18 into a step-by-step rotative movement of the shaft 9. The ratchet contains 100 105

a tooth for each cam and in addition thereto a tooth for a safety position of the shaft in which latter position all of the bomb hooks will be locked. The shaft is set in this neutral or safety position before the bombs are attached by means of the safety device 18 in Figure 3. The arrangement of the hooks is such that a few large bombs or more small bombs may be fastened in the rack as desired. It is not practicable though to carry large and small bombs in this particular horizontal row.

The solenoid which acts as a prime mover for the bomb releasing shaft, has its coil 15 connected with an electrical control circuit in two ways. It is connected directly in parallel with the circuit and also through an interrupter 19. The circuit is shown in Figure 9 which is a diagrammatic view of 20 the wiring of the control system. We make use of two control switches 20 and 21 which are connected with a source of current 22 and with the solenoid 18 in such a manner that one switch will, when closed, impart a 25 single impulse to the core and cam shaft, whereas the other switch will bring the interrupter 19 into action and cause a series of motive impulses, one for each step of the ratchet movement, to be imparted to the 30 shaft. The former may be termed the "train" switch and the other the "salvo" switch. An electromagnet safety lock 23 is provided for the bomb releasing mechanism and is connected in parallel with the circuit 35 of the solenoid 18. A safety switch 24 is used to close the circuit through a safety lock at the will of the operator.

Referring now to Figures 4 and 5, the control switches are shown in detail. The train 40 switch has a large button 25 adapted to be pressed in an axial direction into the housing of the switch to close the switch and drop one bomb. A coiled torsion spring resists such movement of the button 25 and 45 also tends to rotate the button in its housing during such axial movement. The button is a conductor of electricity and is connected with a binding post 27. It has a tubular contact 28 adapted to engage a plug contact 50 29 insulated from the button and connected with a binding post 30. This contact will occur when the button is pressed. A spring pressed pin 31 mounted in the housing is adapted to work in a cam slot 32 in the cylindrical surface of the button. The location 55 and formation of the slot 32 is illustrated spread out in Figure 7, wherein it will be observed that the slot is staggered or of serpentine formation and extends around the 60 periphery of the button. Each two legs of this slot represent inward and outward movements of the button in closing the circuit once for the release of a single bomb. The pin 31 in following these two legs causes 65 the button to be turned in one direction

through a partial rotation each time the button is pressed. This causes the indicator hand 33 on the head or face of the button to traverse a circular scale in the face of the switch board 34 as shown in Figure 4 bearing indicia representing the number of bombs that still remain in the rack. The hand 33 will thus move step by step from one number to the other, in inverse numerical order, as from 10 to 9 to 8, etc. A notch 75 35 is provided in alternate legs of the slot 32 to receive the end of the pin 31 and prevent retrograde movement of the button when it is pressed by the operator even to a very slight extent. Thus when the button is partially pressed it cannot return to its original position until it has passed through a complete cycle of operation. Pressure on the button is continued by the operator until the button reaches the limit of its movement. 80 On each complete movement of the button a bomb is dropped. The end of the pin 31 is bevelled so that it will leave the notch 35 when the button is forcibly moved in the proper direction. 85

The salvo button is similar in construction except as to the form of cam slot. The development of this slot is illustrated in Figure 8 and is of such form that the button has one step of rotary movement. This is due 95 to the fact that a single impulse releases the entire series of bombs through the action of the interrupter 19 of the solenoid. The interrupter is actuated by a projection 34 on the core of the solenoid which actuates the 100 interrupter bar 35 in turn acting upon a contact spring 36 causing the current to be interrupted and causing the reciprocatory movement to be imparted to the core 17 of the solenoid. 105

The circuits of the electrical wiring system will now be traced. When the train switch 20 is operated, the current passes from the battery 22 through wire 37 and switch 20 which is closed out through wire 110 38 through the coil of the solenoid 18 then through wire 39 through which the current returns to the battery 22.

When the salvo switch 21 is closed, the current from the battery 22 passes through 115 wire 37 and wire 40 through the closed salvo switch 21 and then through wires 41, 42 and 43, to wire 44, thence through the coil of the solenoid 17 and out through wire 45, returning through wire 39 to the battery 22. 120

When the safety switch 24 is closed concurrently with the closing of the salvo switch 21, the salvo circuit functions and in addition thereto current from the battery 22, passes through wire 37 past the train 125 switch 20 which is open, through wire 40, through the salvo switch which is now closed and thence through wires 41, 46, safety switch 34, wire 47, through the coil of the safety lock 23 out through wire 45 and 130

thence through wire 39 back to the battery 22.

In Figures 10 and 11 we have illustrated a construction especially adapted for heavier bombs as well as light bombs. In the lighter bombs only one lug is provided on the bomb and therefore only one hook is necessary for each bomb. Where larger bombs are used, the latter are provided with two lugs and in such case the rack will be provided with a pair of hooks 48 pivotally mounted on the hanger bar as shown in Figure 10 and coupled together by a connecting bar 49. The bar 49 is held in bomb-holding position by means of a trigger 50 having a lip 51 engaging a shoulder or lip 52 on the connecting bar 49. The lever 50 is of the bell crank type and is connected pivotally to another bell crank lever 53 having a notch 54 which receives a cam 55 on the rotatable cam shaft 56 as shown in Figure 11. The same principle is embodied in the structure shown in Figures 10 and 11 as in Figures 1, 2, and 3. The construction described in connection with Figures 10 and 11 enables both large and small bombs to be carried in the same rack.

We claim—

1. In combination with a bomb-supporting frame member, a bomb-supporting hook, a trigger for locking said hook, and a rotary cam shaft having a cam to operate said trigger to release the hook, said cam being movable longitudinally of said shaft.
2. In combination with a bomb-supporting frame member, a bomb-supporting hook, a trigger for locking said hook, a cam shaft and a cam rotatable with said shaft to operate said trigger to positively release the hook, said cam being movable longitudinally of the shaft in one direction to admit of manual movement of the trigger to enable a bomb to be placed on the hook.
3. In combination with a bomb-supporting frame member, a bomb-supporting hook, a trigger for locking said hook, a cam shaft, and a cam rotatable with said shaft to operate said trigger to positively release the hook, said cam being movable longitudinally of the shaft in one direction to admit of manual movement of the trigger to enable a bomb to be placed on the hook, a stop collar on the shaft at one side of the cam, and yieldable means to hold the cam against said collar.
4. In combination with a bomb-supporting frame member, a series of bomb-supporting hooks, a trigger for each hook, and a rotary cam shaft having an operating cam for each trigger, said cam being movable longitudinally of said shaft.
5. In combination with a bomb-supporting frame member, a series of bomb-supporting hooks, a trigger for each hook, and a rotary cam shaft having an operating cam

for each trigger, said cams being set to operate the triggers successively, said cams being movable longitudinally of said shaft against resilient holding means.

6. In combination with a bomb-supporting frame member, a series of bomb-supporting hooks, a trigger for each hook, and a rotary cam shaft having an operating cam for each trigger, said cams being set to operate the triggers successively, said cams being movable longitudinally of said shaft against resilient holding means and means for imparting a step by step rotative movement to said shaft.

7. In combination with a bomb-supporting frame member, a series of bomb-supporting hooks, a trigger for each hook, and a rotary cam shaft having an operating cam for each trigger, said cams being set to operate the triggers successively, and electrical means for turning said shaft with a step by step movement, said cams being movable longitudinally of said shaft against resilient holding means.

8. In combination with a bomb-supporting frame member, a series of bomb-supporting hooks, a trigger for each hook, and a rotary cam shaft having an operating cam for each trigger, said cams being set to operate the triggers successively, and electrical means for turning said shaft with a step by step movement, said electrical means comprising solenoid and pawl and ratchet elements, said cams being movable longitudinally of said shaft against resilient holding means.

9. In combination with a bomb-supporting frame member, a series of bomb-supporting hooks, a trigger for each hook, and a rotary cam shaft having an operating cam for each trigger, said cams being set to operate the triggers successively, and electrical means for turning said shaft with a step by step movement, the last named means including a solenoid, transmission means operated by said solenoid to rotate said shaft, and a switch-controlled circuit including said solenoid, said cams being movable longitudinally of said shaft against resilient holding means.

10. In combination with a bomb-supporting frame member, a series of bomb-supporting hooks, a trigger for each hook, and a rotary cam shaft having an operating cam for each trigger, said cams being set to operate the triggers successively, and electrical means for turning said shaft with a step by step movement, the last named means including a solenoid, transmission means operated by said solenoid to rotate said shaft, and a switch-controlled circuit including said solenoid, and an interrupter in said circuit.

11. In combination with a bomb-supporting frame member, a series of bomb-supporting hooks, a trigger for each hook, and a ro-

tary cam shaft having on operating cam for each trigger, said cams being set to operate the triggers successively, and electrical means for turning said shaft with a step by 5 step movement, the last named means including a solenoid, transmission means operated by said solenoid to rotate said shaft,

an electric circuit in which said solenoid is included, a train switch in said circuit, and a salvo switch also in said circuit.

In testimony whereof we affix our signatures.

HERBERT O. RUSSELL.
CHARLES LEIGH PAULUS.
